COIL FORM AND THE LIKE

William F. Stahl, Evanston, Ill.

Application March 7, 1941, Serial No. 382,130

3 Claims. (Cl. 242—119)

This invention relates to a coil form and the like. It is particularly useful as a bobbin or spool for coil windings or other windings, and obviously will be applicable to other uses.

An object of the invention is to provide a small and inexpensive structure which is extremely sturdy and which, although made of light materials, serves to securely house windings which may be partially of metal and other heavy material. A further object is to provide a new method and means for providing a supporting structure for windings, the structure being formed of very light material which is converted into an extremely strong structure. Other specific objects and advantages will appear as the specification proceeds.

The invention is illustrated in specific embodiments by the accompanying drawing, in which—

Figure 1 is a perspective view of a spool or bobbin embodying my invention; Fig. 2, a perspective view of the core employed; Fig. 3, a perspective view of one of the flanges used; Fig. 4, an enlarged longitudinal sectional view, the section being taken as indicated at line 4 of Fig. 1; Fig. 5, an end view of a modified form of structure; Fig. 6, an end view of one of the flanges employed; Fig. 7, a perspective view of the core; and Fig. 8, a broken part sectional view, the section being taken as indicated at line 8 of Fig. 5.

In the form of the invention illustrated in Figures 1 to 4 inclusive, 10 designates a core which may be formed of any suitable material in any desired manner. Such a core may be formed by winding adhesive tape around a mandrel of square, round or other shape to form a core of the desired shape. The ends of the core are provided with notches or recesses 11 for a purpose which will be later described.

The end flange 12 may be formed of paper, fiber, Bakelite, or any other suitable material. The flange is provided with a central opening 13 and with integral tongues 14 which project into the opening 13.

In the assembly operation, the flanges 12 are inserted over the core ends, and the tongues 14 are brought into engagement with the slots 11 of the core. This leaves a forward portion of each core end projecting beyond the flange 12. The ends are then swaged outwardly and rearwardly to form locking rims 15 bearing against the flanges 12. By interrupting the end portions of the core with slots 11, it is found that the core can be turned smoothly and uniformly into contact with the flanges 12 without tendency to

break or form weakening fissures. Whereas, if the end portions of the core were uninterrupted, they would be annular in form and any attempt to swage such portions outwardly would increase the diameter thereof and tend to break or tear the material, with the present construction the end portions, being interrupted are semi-circular and are not subject to this difficulty.

After the structure has been formed with the flanges secured by means of the rim 15, I immerse the entire form in a solution of a hardening varnish, lacquer, or condensation product, such as phenol formaldehyde solution. The layer of varnish or hard material penetrates the rim and also the slot spaces and, upon hardening, permanently locks the rim in position and also the tongues 14 within the slots 11. If paper is employed, as is customary, the hardening solution causes the tongues 14 to become rigid members and the rims 15 to become rigid shoulders.

When the wire or other winding is wound upon the central core portion, pressure is exerted outwardly against the flanges 12, and it will be noted that pressure against the flanges is sustained by the rims 15 and the tongues 14. The tongues 14, on their inner faces, bear against the ends of the core and thus the flange is locked between the rim and the core. Any tendency for the flanges to swing outwardly away from each other at their outer peripheries upon the fulcrum provided by the rims is prevented by the engagement of the tongues against the end. Further, the tongues prevent any tendency of the flanges to rotate during the winding operation.

The entire operation is simple and as a result of it, an extremely sturdy spool is provided, even though formed of fragile material, such as paper or tape.

In the modified form of structure shown in Figures 5 to 8, the core 16 is provided with four slots 17, a projecting lip 18 being provided between each of the slots. The end flange 19 is provided with four curved slots 20 adapted to receive the lips 18. In the assembled structure illustrated in Figures 5 to 8, the lips 18 are turned either toward or away from the axis of the spool or core to form locking rims against the end flange 19. In the illustration given, the lips are turned toward the axis and inwardly with respect to the center of the spool. After the swaging back of the portions 18, the hardening solution or material is brought into contact with the parts to saturate them and set them in their assembled position. The solution anchors the lips

18 firmly within the slots and the rim portions rigidly against the flanges 18.

It will be understood that the hardening material is used with a paper or soft core and would not be used with a core formed of hard material.

Usually the core 16 is formed by winding gummed tape, forming a series of laminations. The swaging of the ends serves to break the laminations and provides recesses to receive the hardening material. Thus, after the dipping operation, the assembled spool or bobbin is permanently secured in the position shown upon the drying of the solution.

Referring once more to the structure shown in Figures 1 to 4 inclusive, it will be noted that the core extends through the central portion of the flanges and that the cuts formed in the core serve a dual purpose. They receive the locking tongues and at the same time break the end portions so as to permit a smooth bending of the rim during the swaging operation. Further, the openings serve as means for locking the tongues therein when the hardening solution is applied.

While in the foregoing specification, I have set forth certain details and steps as illustrative of the method and product, it will be understood that wide variation therein may be made without departing from the spirit of my invention.

I claim:

1. A form for windings and the like, comprising a tubular core having short longitudinally-extending slots in opposed portions of one of the ends thereof, and a flange mounted at said end of said core in a plane transverse to the axis of the core, said flange having a central opening receiving the core and having radial tongues extending inwardly from the periphery of said central opening received within said slots, each of said tongues being of a length substantially the same as the thickness of the wall of the core 40 and being in engagement with the wall of the core at the base of the longitudinal slot within which the tongue is received, said end portion of the core extending beyond the flange and being struck outwardly and rearwardly to form a locking rim in engagement with the flange. 45

2. A form for windings and the like, comprising a tubular paper core having short longitudinally-extending slots in opposed portions of each of the ends thereof, and a flange mounted at each end of said core in a plane transverse to the axis of the core, said flange having a central opening receiving the core and having radial tongues extending inwardly from the periphery of said central opening received within said slots, each of said tongues being of a length substantially the same as the thickness of the wall of the core and being in engagement with the wall of the core at the base of the longitudinal slot within which the tongue is received, the end portions of the core extending beyond the flanges and being struck outwardly and rearwardly to form locking rims in engagement with the flanges.

3. A form for windings and the like, comprising a laminated tubular paper core having short longitudinally-extending slots in opposed portions of each of the ends thereof, and a flange mounted at each end of said core in a plane transverse to the axis of the core, said flange having a central opening receiving the core and having radial tongues extending inwardly from the periphery of said central opening received within said slots, each of said tongues being of a length substantially the same as the thickness of the wall of the core and being in engagement with the wall of the core at the base of the longitudinal slot within which the tongue is received, the end portions of the core extending beyond the flanges and being struck outwardly and rearwardly to separate the laminations of the end portions thereof and to form locking rims in engagement with the flanges, and a hard material within the space between the separated laminations of said end portions of the core and adhering thereto to maintain said end portions in rearwardly-turned position, said hard material adhering also to the flanges and the radial tongues thereof.

WILLIAM F. STAHL.
